FIG. 1.

FIG. 4.

FIG. 3.

FIG. 2.

The side opposite that shown in FIGURE 3 is substantially similar to that shown, and the rear is a substantially planar surface.

The lamp shade and the light bulbs and socket structures therefor are shown for illustrative purposes only.

I claim:

The ornamental design for a lamp or similar article, as shown and described.
